(57) **CLAIM**

The ornamental design for a display screen or portion thereof with a graphical user interface, as shown and described.

DESCRIPTION

The FIGURE is a front view of a display screen or portion thereof with a graphical user interface.

The dot-dot broken line shown in the drawing forms a part of the claimed design. The dash-dash broken lines and the broken line text shown in the drawing illustrate a device and/or portions of the display screen or portion thereof with a graphical user interface that form no part of the claimed design.

1 Claim, 1 Drawing Sheet
